UNITED STATES PATENT OFFICE.

RICHARD S. MURRELL, OF COLUMBUS, OHIO, ASSIGNOR OF ONE-THIRD TO CLARENCE W. SHIGLEY, OF COLUMBUS, OHIO.

LOCK.

Application filed October 8, 1920. Serial No. 415,543.

To all whom it may concern:

Be it known that I, RICHARD S. MURRELL, a citizen of the United States of America, residing at Columbus, in the county of 5 Franklin and State of Ohio, have invented certain new and useful Improvements in Locks, of which the following is a specification.

My present invention relates generally to 10 locks applicable to locker doors, automobiles, residences, vaults, public buildings, offices, and in fact practically everywhere that special locking facilities are required, and is more particularly that type of lock, 15 usually coin controlled, where, upon the shifting of the locking bolt or member, a key disk and the like is discharged into the hands of the user and is required for subsequent insertion in order to shift the lock 20 to open position.

It is a common disadvantage of locks of 25 this type which employ a key disk, that nothing prevents the user from having duplicates of the key disk made while in his possession, which he can subsequently use to open a locked door in an unwarranted manner.

The primary object of my invention is 30 to provide a lock of the above type in which the above disadvantage is not present and in which the subsequent unwarranted use of duplicates previously made is so unlikely to be successful as to make its attempt impractical.

Generally speaking my invention proposes to attain this object by a lock in which 35 a number or series of key disks are used in successive manner, each key being different from the others, in connection with means 40 whereby upon its discharge each key disk sets a mechanism preventing subsequent re-opening of the lock except by the use of the identical key disk dispensed or discharged during the previous locking operation. The setting mechanism just referred 45 to partakes to a considerable extent of the nature of the tumblers of a lever lock, in fact its principal components are tumbler levers, and the lock as a whole is a keyless lock in the sense that the usual bolt throwing key is avoided, the bolt moving to locked position either with or without requiring a coin for this purpose, and shifting in the opposite direction to unlocked position, only

in the presence of that key disk discharged 55 at the previous locking operation.

Thus by the use of a series of key disks in the manner I will presently describe, the danger of fraud and theft is avoided and an element of safety assured which cannot 60 reside in those locks of its class now in use.

In the accompanying drawings which illustrate my invention and form a part of this specification. 65

Figure 1 is a front view of the lock mechanism in unlocked position with the front wall of the casing removed,

Figure 2 is a similar view with the parts in locked position, 70

Figure 3 is another similar view with the parts partially shifted to locked position, certain parts being in section,

Figure 4 is a view like Figure 3 showing the parts partially shifted to unlocked position, 75

Figure 5 is a side view of the mechanism looking from the left of Figure 1, with the left side wall of the casing removed,

Figure 6 is a similar view looking in the 80 opposite direction,

Figure 7 is a plan view of the mechanism with the top of the casing removed, the parts being in the position of Figure 1,

Figure 8 is a similar view with the parts 85 in the position of Figure 2,

Figure 9 is a cross section taken on line 9—9 of Figure 4,

Figure 10 is a top plan view of one of the key disks, 90

Figure 11 is a side view thereof,

Figure 12 is a detail view showing the disk receiving aperture of the casing,

Figure 13 is a detail side view of the bolt carriage removed, 95

Figure 14 is a partial side view thereof,

Figures 15 and 16 are cross sections taken respectively on lines 15—15 of Figure 3 and 16—16 of Figure 4,

Figures 17 and 18 are respectively a side view and top plan of the carriage supporting bracket removed, 100

Figure 19 is a partial side view illustrating a slightly modified form, and,

Figure 20 is an elevation showing one of 105 the many applications of the invention.

Referring now to these figures, I have shown in Figures 1 to 4 particularly a rec-

tangular lock casing including a rear plate 25, side walls 26 and 27, a top wall 28, and a front wall 29, see Figures 7 and 8, which has an upper coin receiving slot, a lower 5 disk discharge opening and a disk receiving slot between the coin slot and discharge opening, respectively registering with the coin slot 30, disk discharge opening 31 and disk receiving slot 32 of a door casing and 10 the like which may be the frame of a locker 33 as in Figure 20, adjacent to the door 34 whose control is sought to be effected. This latter figure in particular illustrates the adaptability of the lock as 15 a whole to doors opening in relatively opposite directions and located in adjacent relation to one another.

Through the front of the door frame projects a bolt operating handle 35, fixed 20 to the forward end of a shaft 36 which is journaled through the rear and front plates 25 and 29 and extends loosely through the side wings 37 of a bolt throwing member 38 which swings in the casing with rotation 25 of the shaft. The shaft also extends loosely through one end of an actuating arm 39, one end of which is engageable by the member 38 and the lower end of which is connected by a spring 40 with the upper 30 end of a vertically shiftable locking slide 41 mounted to move upon the inner surface of the side wall 27.

The bolt throwing member 38 has its lower portion straddling the bolt 42 and 35 also has a coin chute 43 which in the normal unlocked position shown in Figure 1 has its upper end opposite the coin slot and has its lower end alined above a transverse recess 44 in the upper edge of the 40 sliding bolt 42, so that a coin 45, resting partially in this recess and partially within the coin chute, forms a connection between the swinging member 38 and the bolt 42 by means of which the latter may be shifted 45 to the locked position of Figure 2 with its free end projecting externally through an opening in the side wall 26. The coin chute 43 has a side wing 46 which moves opposite the coin receiving slot as the member 38 is shifted to locked position as in 50 Figure 2 and prevents the entrance of another coin while the bolt is locked.

In order that the member 38 can yield to a slight extent at the limits of its movement, the connection between the same and the shaft 36 is in the nature of a spring 47 coiled around the shaft with one end connected thereto and the other end connected to member 38, the latter operating in its 60 swinging movement to locked position, to shift the locking slide 41 downwardly in order to project its lower locking block 48 between the inner end of bolt 42 and the side wall 27. For this purpose member 38 65 engages arm 39 which is connected to the

upper portion of one of the wings 37 by a spring 49 to provide for its subsequent upward movement.

The bolt 42 has a depending carriage shiftable therewith and is guided in its movement by its free end in the wall opening and by a bracket 50 secured to the side wall 26 the upper, inner portion of which carries a transverse guide pin 51 projecting through a lengthwise slot 52 of the 70 bolt. The bolt carriage as seen particularly in Figure 13 includes an upright 53 having at its lower end inward angular extensions 54 and having upper vertically spaced horizontally disposed shelves 55 and 56, the former constituting a disk receiving plate and the latter constituting a disk storage plate. At its inner end bolt 42 also has a depending extension 57 whose side plate 58 75 opposes the disk storage station and terminates at its lower end a distance above the disk storage plate 56 of about the thickness of one of the unlocking or key disks 59. This extension 57 has an upper plate 60 slightly below the level of the disk receiving plate 55 and adjacent to the same for a purpose to be presently described.

The inner ends of the lower angular extensions 54 of the bolt carriage are connected by a transverse pin or shaft 61 upon which the lower ends of a series of tumblers or lock setting levers 62 are mounted in a series between a pair of disk guiding levers 63. Each of the several levers 62 and 63 is connected to the carriage upright 53 by a spring 64 and the levers or tumblers 62 have upper recessed ends or heads 65 to cooperate with a rectangular locking frame 66 at the lower portion of the locking slide 41. The levers 63 terminate below the upper ends of levers 62 and, like the latter, are independently swingable inwardly by the recessed edge of the lowermost key disk of the vertical series of superposed key disks 90 on the disk storage plate 56.

The bracket 50 has a lower inwardly projecting fork 67 which, during movement of the bolt 42 to locked position extends through apertures in the carriage upright 53 and, being rigid and disposed in the plane of the lowermost key disk of the series, forces said key disk from beneath the others and against the levers 63 and also the tumblers 62 except those alined with the recesses of the key disks. This movement of the parts appears in Figure 3 and by means thereof certain of the tumblers are shifted inwardly to receive thereover, and engage, the locking frame 66. The other tumblers remain outside this frame and are subsequently prevented thereby from inward shifting movement.

Thus in the locked position shown in Figure 2 the locking engagement between cer-

tain of the tumblers 62 and the frame 66, holds the slide 41 in lowered position, so that its block 48 prevents inward movement of the bolt. When the parts have been 5 locked and pressure on the handle is released, the key disk pressed out of the series of disks as in Figure 3, is shifted downwardly into a key disk discharge chute 68 carried by the upright 53 and the latter 10 registers, in this position of the bolt, with the key disk discharge opening 31. The key disk is shifted at this time into this chute by the arms 63 under tension of their spring 64 as seen in dotted lines in Figure 15 3, and the operator thus becomes possessed of a key disk different in recessing from all other keys of the series, and the only one of the series capable of releasing the lock as it has, in discharging from the vertical 20 series of disks, practically set its own combination.

For releasing the lock by shifting the locking bolt 42 inwardly, the lower portion of the bolt shifting member 38 is movable 25 against laterally projecting pins 69 of the bolt, see Figures 4 and 9, but until the proper key disk is inserted through slot 32, the bolt cannot be shifted. When the proper key disk is inserted it is positioned on the disk 30 receiving plate 55 in the position shown in dotted lines in Figure 3 so that the lower angular portions 70 of the side wings 37 of the bolt throwing member will engage the same upon turning of the handle 35 in the 35 proper direction.

During the swinging movement of member 38 to the position of Figure 4 it is obvious such movement takes place relative to the arm 39, the latter remaining practically 40 stationary as the key disk is shifted inwardly into engagement with the tumblers 62 which were previously pressed inwardly. As soon as these tumblers are freed from the frame 66, the slide 41 shifts upwardly 45 by virtue of the tension of spring 49. In pressing the tumblers 62 inwardly, the key disk has also engaged and pressed the levers 63 inwardly so that when the disk is pushed inwardly beyond the inner edge of the disk 50 receiving plate 55, and pressure released, it drops and levers 63 shift the same forwardly onto the stack of disks resting on the storage plate 56.

At about the same time the tumblers 62 55 are released from the frame 66, the lower portion of member 38 engages the pins 69, thus at a time when the bolt 42 is free to shift inwardly to the normal released position of Figure 1 upon further swinging 60 movement of the handle.

Thus at each bolt releasing operation, the key disk withdrawn from the bottom of the stack or magazine, is returned to the top thereof, and it is thus obvious that the same 65 key disk is used once in so many operations

only, dependent upon the number of key disks in the magazine. It is also obvious that with a plurality of tumblers 62 the range of variation in the formation of the recessed edges of the disks is extremely wide, 70 the number of combinations far beyond the requirements.

The lock proposed is strong, durable, of 75 comparatively simple construction, the several parts capable of ready quick manufacture in large numbers, and the structure as a whole obviously avoids the difficulties and disadvantages of those known at the present time.

Furthermore, that the use of a coin controlling feature is not absolutely essential, see Figure 19 wherein the operating parts are the same as previously described except that the bolt throwing member 38^a has no coin chute and engages an upright projection 71 of the bolt 42^a to throw the latter to locked position.

As before stated, when the parts are in the normal inactive position of Figure 1, the coin chute 43 is opposite the coin receiving slot 30 and when a coin has been inserted and the parts shifted to the locked position of Figure 2 the coin receiving slot is covered by the wing 46 so that a coin cannot be thoughtlessly placed in a lock already in use. In a similar manner, when the parts are in the locked position of Figure 2 the disk magazine and disk discharge chute are respectively opposite the disk receiving aperture 32 and disk discharge slot 31, but 100 when the parts are again in the position of Figure 1, the adjacent side of the carriage upright 53 closes said aperture and said slot both against unwarranted withdrawal of a disk and insertion of a key belonging to another lock.

I claim:

1. In a lock, a bolt, manually actuated means for shifting the bolt to locked and released positions, a single bolt locking member shiftable by said manual means into the path of retractile movement of and engageable with the bolt when the latter is in locked position, a series of tumblers selectively movable to engage and hold the bolt locking member in effective position, a magazine, and a series of successively operable tumbler controlling members in the magazine, having differently positioned tumbler shifting means and having individual movement into engagement with the tumblers within and from the magazine upon actuation of the said manual bolt shifting means.

2. In a lock, a bolt, manually actuated means for shifting the bolt to locked and released positions, a single bolt locking member movable into and out of effective position for securing the bolt in the locked position of the latter, a series of selectively operable tumblers lockingly engageable with the bolt 130

- securing member when the latter is in effective position, and a series of successively operable tumbler controlling members individually dischargeable from and insertable within the lock, having differently positioned tumbler engaging and shifting means for the purpose described.
3. In a lock, a bolt, manually actuated means for shifting the bolt to locked and released positions; a single bolt locking member movable into and out of effective position for securing the bolt in the locked position of the latter, a series of selectively operable tumblers lockingly engageable with the bolt securing member when the latter is in effective position, and a series of successively operable tumbler controlling members individually dischargeable from and insertable within the lock, having differently positioned tumbler engaging and shifting means, and a magazine within the lock from one end of which a tumbler controlling member is dischargeable and into the opposite end of which the tumbler controlling member is insertable.
4. In a lock, a manually shiftable bolt, a carriage supported by and movable with the bolt having a magazine, a series of members having different tumbler controlling means in the magazine, each dischargeable from one end of the magazine and insertable within the opposite end, means to discharge one of the said members during movement of the bolt to locked position, a bolt locking member shiftable into and out of effective position in the path of retractile movement of the bolt, and a series of tumblers engageable and controlled by the members of the magazine during movement of the latter into and out of the magazine, said tumblers being lockingly engageable with the bolt locking member when the latter is moved to effective position.
5. In a lock, a manually shiftable bolt, a carriage supported by and movable with the bolt having a magazine, a series of members having different tumbler controlling means in the magazine, each dischargeable from one end of the magazine and insertable within the opposite end, means to discharge one of said members during movement of the bolt to locked position, a bolt locking member shiftable into and out of effective position in the path of retractile movement of the bolt, and a series of tumblers engageable and

controlled by the members of the magazine during movement of the latter into and out of the magazine, said tumblers being lockingly engageable with the bolt locking member when the latter is moved to effective position, and being arranged in a series on the bolt carriage opposite the said magazine and pivoted at one end for the purpose described.

6. In a lock, a manually shiftable bolt, a carriage supported by and movable with the bolt having a magazine, a series of members having different tumbler controlling means in the magazine, each dischargeable from one end of the magazine and insertable within the opposite end, means to discharge one of the said members during movement of the bolt to locked position, a bolt locking member shiftable into and out of effective position in the path of retractile movement of the bolt, and a series of tumblers pivoted on the carriage and selectively shiftable into and out of locking engagement with the bolt locking member under control of said magazine members during discharge of the latter from and insertion within the magazine.

7. In a lock, a bolt, a controlling handle, a swinging bolt shifting member having a yielding connection with the handle, a bolt locking member, an arm for shifting the bolt locking member into effective position having a movable connection with said bolt shifting member, a series of selectively movable tumblers each of which is lockingly engageable with the bolt locking member in the effective position with the latter, a carriage supported by and movable with the bolt, upon which the said tumblers are movably mounted, a magazine in connection with the carriage, and a series of tumbler controlling members in the magazine successively shiftable from one end of the same and dischargeable from the lock during effective movements of the bolt to locked position, each of said members being insertable into the opposite end of the magazine and each thereof having selectively positioned tumbler engaging portions engageable with the tumblers to respectively set and release the same upon movement of the members out of and into the magazine.

In testimony whereof I have affixed my signature.

RICHARD S. MURRELL.
